Des. 205,263
Patented July 12, 1966

205,263

COOKING STOVE

Walter Dorwin Teague, Jr., Glen Goin Road, Alpine, N.J.,
and Anthony Montalbano, 24-09 87th St., Jackson
Heights, N.Y.

Filed July 2, 1965, Ser. No. 86,001

Term of patent 14 years

(Cl. D81—25)

Fig. 1

Fig. 2

Fig. 3

Fig. 4

FIGURE 1 is a top plan view of the cooking stove; FIGURE 2 is a front elevation of the cooking stove; FIGURE 3 is a side view of the cooking stove from the left of FIGURE 1, the side view from the right being a mirror image; and,

FIGURE 4 is a view similar to FIGURE 3 with parts cut away to show the details at the front of the cooking stove.

We claim:

The ornamental design for a cooking stove, substantially as shown and described.
